Primary Examiner — Robin V Webster*Assistant Examiner* — Rachel Voorhies(74) *Attorney, Agent, or Firm* — Ballard Spahr, LLP(57) **CLAIM**

I claim the ornamental design for a portion of a display panel with a set of computer icon images, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first portion of a display panel with a set of computer icon images in a sequence of four images displayed on a portion of a display panel;

FIG. 2 is a front view of a second portion of a display panel with a set of computer icon images in a sequence of four images displayed on a portion of a display panel;

FIG. 3 is a front view of a third portion of a display panel with a set of computer icon images in a sequence of four images displayed on a portion of a display panel; and,

FIG. 4 is a front view of a fourth portion of a display panel with a set of computer icon images in a sequence of four images displayed on a portion of a display panel.

The claimed design is directed to a graphical user interface comprising computer-generated icons embodied in a display panel. The claimed design is directed to the collective appearance of the images shown. The broken lines showing the display panel, icons, and text are for illustrative purposes only and form no part of the claimed design. The appearance of the image set which is shown in FIG. 1 transitions sequentially to the image set shown in FIG. 2, which image set transitions sequentially to the image set shown in FIG. 3, which image set transitions sequentially to the image set shown in FIG. 4. The process or period in which one image set transitions to another image set in FIGS. 1-4 forms no part of the claimed design.
